UNITED STATES PATENT OFFICE.

ELDRIDGE J. SMITH, OF WASHINGTON, DISTRICT OF COLUMBIA, ASSIGNOR
TO THE STREET CLEANING COMPANY, OF SAME PLACE AND ALEXAN-
DRIA, VIRGINIA.

STREET-SWEEPER.

SPECIFICATION forming part of Letters Patent No. 606,248, dated June 28, 1898.

Application filed September 10, 1897. Serial No. 651,207. (No model.)

To all whom it may concern:

Be it known that I, ELDRIDGE J. SMITH, a citizen of the United States, residing at Washington, in the District of Columbia, have invented certain new and useful Improvements in Portable Street-Sweepers; and I do hereby declare the following to be a full, clear, and exact description of the invention, such as will enable others skilled in the art to which it appertains to make and use the same.

My present invention relates to improvements in hand-operated and hand-propelled street sweepers or cleaners, and has for its objects to provide a device of this character which will be simple and cheap in its construction, light and easy of manipulation, and one comprising a comparatively few number of parts.

It is the purpose of my invention to provide a street sweeper or cleaner that can be readily and easily propelled by a person with comparatively little exertion and which will effectively perform the work for which it is intended.

It is a further purpose of my invention to provide improved and novel mechanism for operating the rotary brush, and it is a still further purpose of the invention to provide a novel and simple manner of fastening the tufts into the brush-head.

Briefly stated, my invention comprises a box or carrier preferably mounted on wheels and provided with a handle by which it can be propelled or advanced forward, a rotary brush mounted at the front or mouth of the box or carrier, and mechanism operated by oscillating the handle whereby the brush may be given a continuous or intermittent rotary movement in the same direction to suit the will of the operator.

To these and other ends the invention comprises the novel features of construction and combinations of parts hereinafter described and then more definitely pointed out in the claims.

In order to enable others skilled in the art to make and use my invention, I will proceed to describe the same in detail, reference being had for this purpose to the accompanying drawings, in which—

Figure 1 is a perspective view of one form

of street-cleaner constructed in accordance with my invention. Fig. 2 is a view of the rotary brush. Figs. 3 and 4 are detail views of the brush, showing the manner of securing the tufts to the head. Fig. 5 is a perspective view of one of the adjustable bearing-plates for the brush. Fig. 6 is a detail sectional view showing one manner of securing the scraper-blade in position upon the bottom of the box or carrier. Fig. 7 is an enlarged detail view of one form of mechanism for imparting a rotary motion to the brush. Fig. 8 is a vertical section of the same, taken on the line *xx*, Fig. 7. Fig. 9 is a detail view of a modified form of device for shifting the ratchet-yoke into and out of engagement with the ratchet-wheel. Fig. 10 is a vertical section of the same, taken on the line *yy*, Fig. 9. Fig. 11 is a detailed plan view of the rear end of the lower yoke projection illustrated in Fig. 9. Fig. 12 is a perspective view showing another form of receiving-box, with the rear door shown closed in full lines and open in dotted lines. Fig. 13 is a perspective view of one of the rear-door-retaining clips. Fig. 14 is a perspective view of the stationary plate 30, oscillating part 35, and spring 37, illustrated in Fig. 9.

Referring now to the drawings, the reference-numeral 1 designates the sides at the box or receiver, and 2 the top, which is preferably composed of sheet metal and tacked on or otherwise secured to the sides. To the rear of the box, upon each side, is secured one end of an upward and rearwardly extending spring-metal bar 3, the upper portion of which is bent, as shown in Fig. 1, and secured to a wooden or other block 4, and the lower ends of this metal bar 3 are bent slightly outward, as at 5, to provide a space for the runner-wheels 6, which latter are journaled in the ends of said bar and in the sides of the box.

The front portion of the box or receiver is open to receive the litter or dirt, and projecting from the lower front edge of the box is a scraper-blade 7, the ends of which are bent upward, as at 8, and secured to the sides of the said box. To the under side of the scraper-blade I secure one or more flanged plates 9, as shown in Fig. 6, which project beyond or overhang the edge of the box-bottom 10, so

as to securely retain the blade in position. It will thus be seen that the scraper-blade can be easily and quickly removed when occasion demands, and to accomplish this it is only necessary to remove the screws by which it is secured to the sides of the box or receiver. The rear end of the box is provided with a hinged door 12, which is held closed by hooks 12', as shown in Fig. 1, or preferably held closed by gravity-catches 13, one of which is shown in detail in Fig. 12. This end door is preferably hinged at its lower edge, so that it will fall open by gravity when the hooks 12' or catches 13 are thrown out of engagement with it.

To the front or mouth of the box or receiver, about midway between the top and bottom thereof, is mounted a rotary brush, the shaft 15 of which is journaled in adjustable bearing-plates 16, which are secured to the sides of the box or receiver, as shown in detail in Fig. 5. Each of the bearing-plates 16 is provided with one or more slots 17, through which the fastening-screws 18 are passed, and projecting from the front edge of each plate is an apertured ear 19, which forms a bearing for the brush-shaft 15. By reason of the slots 17 and screws 18 the bearing-plates can be adjusted up or down, so as to shift the position of the brush with relation to the scraper-blade as it becomes worn. To one end of the brush-shaft 15 is keyed a ratchet-wheel 20, upon either side of which is a circular plate or disk 21 for the purpose of guiding the forward end of the ratchet-yoke, hereinafter to be described.

The mechanism for imparting a rotary motion to the brush comprises a pair of ratchet-bars 22 and 23, which are made to alternately engage with the upper and lower teeth of the ratchet-wheel when reciprocated back and forth, so as to rotate the brush in one direction only, either continuously or intermittently. For convenience I will term the ratchet-bars 22 and 23 a "ratchet-yoke," since they are secured together at their front and rear ends, as shown. Projecting backward from the lower ratchet-bar is an extension-piece 24, which may be curved downward, as at 25, Fig. 7, or which may be straight, as at 26, Fig. 9. In construction the distance between the ratchet-bars 22 23 is slightly greater than the diameter of the ratchet-wheel 20, and in order to impart a continuous rotary movement to the brush it is necessary to throw the ratchet-bars 22 and 23 alternately into and out of engagement with the ratchet-wheel. The teeth of the upper ratchet-bar 22 rest by gravity upon the upper edge of the ratchet-wheel and are arranged to rotate the said wheel when driven forward only. It is necessary now to provide some means for throwing the teeth of the upper bar out of engagement with the ratchet-wheel and likewise throw the teeth of the lower ratchet-bar into engagement, so that when the ratchet-yoke is drawn backward the teeth of the said lower

bar 23 will engage with the under edge of the ratchet-wheel and continue the rotary movement started by the upper ratchet-bar 70 in its forward movement. I have shown several ways of thus shifting the ratchet-yoke, as will be seen by referring to the drawings. In Figs. 1, 7, and 8 this mechanism comprises an oscillating plate 27, pivoted to the side of 75 the box or receiver, as shown in cross-section in Fig. 8. To the said oscillating plate 27 is fixed a horizontal ledge or projection 28, upon which rests and abuts the rearward curved extension 25 of the ratchet-yoke, and to the 80 front of said oscillating plate is screwed a spring-plate 29, that is adapted to exert a slight frictional pressure upon the side face of the extension-piece 24, just sufficient to insure the movement or oscillation of the plate 85 27 with the movement of the ratchet-yoke. The spring-plate 29 projects somewhat above the extension-piece 24 and acts as a guide for the same.

Figs. 9, 10, and 11 represent modifications 90 of the mechanism for shifting the ratchet-yoke. In Fig. 9 the reference-numeral 30 indicates a vertically-adjustable plate which is secured to the side of the box or receiver and is provided with stop-lugs 31 and 32, 95 the latter one of which has an inclined stop-wall 33. Pivoted to the plate 30 at 34 is an oscillating plate 35, provided with an inclined ledge or shoulder 36, (shown in dotted lines in Fig. 9,) and upon which rests the 100 straight extension 26 of the ratchet-yoke. To the oscillating plate 35 is secured a spring-plate 37, which is adapted to exert a pressure upon the side face of the extension 26 to cause the oscillating plate 35 to move with the movement of the ratchet-yoke, for the purpose heretofore set out with reference to the structure shown in Figs. 7 and 8. The spring-plate 37 may be made to exert a greater or less pressure upon the extension 26 by tightening or loosening the screw 38. The stop-lugs 31 32 act to limit the movement of the oscillating plate 35, as will be understood. In practice I prefer to gradually widen the extension-piece 26 toward its rear ends, as at 110 39, as shown in plan view in Fig. 11, so as to secure a proper frictional contact with the spring-plate 37.

The mechanism for operating or reciprocating the ratchet-yoke comprises a rod 45, which is attached to said yoke, as shown, the angle between these parts being substantially obtuse, and the outer end of said rod 45 is pivoted to an oscillating handle 46, that is pivoted to the block 4. The said handle 46 is 120 preferably provided with handholds 47, whereby ease in operation is effected. In order to limit the movement of the oscillating handle 46, I have provided an adjustable stop-plate 48, as shown in Fig. 1, said stop being provided with a slot-and-screw connection with the block 4, whereby it may be adjusted to and from the handle. Owing to the fact that the bars 3 are made of spring metal, they ef- 130

fectively take up the jar from the oscillating handle striking against the stop-plate 48. Thus the jar is not transmitted to the machine proper as it otherwise would be.

5 My improved manner of forming the brush consists in providing the brush-head 49 with a series of apertures 50, spirally or otherwise arranged around the periphery of said head, and then placing the tufts 51 therein, as 10 shown. After the tufts are inserted into the apertures in the head I drive a block or wedge 52 into each aperture upon each side of the tuft, the blocks thus tending to spread or widen the tufts and at the same time firmly 15 secure them in position in the head. This manner of forming the brush is cheap and simple and produces a very desirable article.

The operation of my improved sweeper will be readily understood from the foregoing description. The box or receiver is propelled or advanced in the direction of the dirt or litter to be gathered, and the same gathers and accumulates upon the scraper-blade. The operator then gives one or two quick oscillatory movements to the handle, whereby 25 the brush is rotated, throwing the accumulated dirt back into the box or receiver.

It is to be noted that it is not necessary to operate the brush continuously; but this may 30 be done, if desired. When the box or receiver becomes loaded or full, the catches holding the rear door are released and the box tilted backward until the handle portion touches the ground, and the contents of the 35 box or receiver will then fall out.

Minor changes or additions to the general construction of my sweeper may be made without departing from the spirit of my invention.

40 What I claim is—

1. In a street-sweeper, the combination with a box or receiver, of a brush journaled upon said box, an oscillating handle, a reciprocating rod operated by said oscillating handle 45 and a connection between said rod and brush whereby the latter is rotated when the rod is reciprocated.

2. In a portable sweeping-machine, the combination with a dirt-receiver, of a brush journaled upon said sweeper, a toothed wheel carried by the brush, a pair of racks arranged respectively above and below the said toothed wheel and adapted to be alternately brought into contact with said wheel to impart a rotary motion thereto, and means for reciprocating the said racks.

3. In a portable street-sweeper, the combination with a box or receiver, of a brush journaled upon said box, a ratchet-wheel carried 60 by the brush, a ratchet-yoke coöperating with the said ratchet-wheel, an oscillating handle, and a connection between said oscillating handle and the ratchet-yoke whereby the brush is given a continuous rotary movement in one direction during the oscillation of the handle.

4. In a portable street-sweeper, the combination with the box or receiver, of a brush

journaled upon the said box, a ratchet-wheel carried by the brush-head, a ratchet-yoke coöperating with the said ratchet-wheel to drive 70 the brush in one direction, means for reciprocating the ratchet-yoke, and mechanism for throwing the teeth of the said ratchet-yoke into and out of engagement with the ratchet-wheel during its rotation.

5. In a portable street-sweeper, the combination with the box or receiver, having an open front end, a brush journaled at the said front end of the box, an oscillating handle, a connection between said handle and brush 80 for imparting a continuous rotary movement to the latter in one direction, and an adjustable stop-plate for limiting the movement of the said oscillating handle.

6. In a portable sweeping-machine, the combination with a wheeled box or receiver having an open front end and a door at the rear end, handle-bars secured to the sides of the said box and having their lower ends bent outward to accommodate the runner-wheels 90 and provide bearings for the runner-wheel axles, a block carried by the upper portion of the handle-bars, an oscillating handle pivoted to said block, a brush journaled at the front end of the box or receiver, a ratchet-wheel carried by the brush, a ratchet-yoke coöperating with the said ratchet-wheel to rotate the brush, and a connection between the ratchet-yoke and oscillating handle to operate the said yoke.

7. In a portable street-sweeper, the combination with a dirt-receiver, of a rotary brush journaled upon said receiver, a ratchet-wheel carried by the brush, a ratchet-yoke coöperating with the brush to impart a rotary movement thereto, an oscillating plate upon which a portion of said ratchet-yoke bears, said oscillating plate being arranged to shift the position of the ratchet-yoke with respect to the ratchet-wheel, and means for reciprocating 105 the ratchet-yoke.

8. In a portable street-sweeper, the combination with a dirt-receiver, of a rotary brush journaled upon said receiver, a ratchet-wheel carried by the brush, a ratchet-yoke coöperating with the ratchet-wheel to impart a rotary movement to the brush, an oscillating plate upon which a portion of said ratchet-yoke rests said oscillating plate being arranged to shift the position of the ratchet-yoke with respect to the ratchet-wheel, and a spring-plate acting upon a part of the said yoke to insure its operation, and means for reciprocating the ratchet-yoke to rotate the brush.

9. In a portable street-sweeper, the combination with a dirt-receiver, of a rotary brush journaled upon said receiver, a ratchet-wheel carried by the brush, a ratchet-yoke coöperating with the ratchet-wheel to rotate the brush, a rearward extension-piece on said ratchet-yoke, an oscillating plate having a ledge or projection upon which said extension-piece rests, said oscillating plate being ar-

ranged to shift the position of the yoke with respect to the ratchet-wheel, and means for imparting a reciprocating movement to the said ratchet-yoke to rotate the brush.

- 5 10. In a portable street-sweeper, the combination with a dirt-receiver, of a rotary brush journaled upon said receiver, a ratchet-wheel carried by the brush, a ratchet-yoke coöperating with the ratchet-wheel to rotate the
10 brush, an oscillating plate upon which the said yoke rests, said oscillating plate being

arranged to shift the position of the yoke with respect to the teeth of the ratchet-wheel, stops for limiting the movement of the said oscillating plate, and means for reciprocating the 15 ratchet-yoke to rotate the brush.

In testimony whereof I affix my signature in presence of two witnesses.

ELDRIDGE J. SMITH.
